Filed Sept. 23, 1958, Ser. No. 762,821
8 Claims. (Cl. 307—88)

This invention relates to logical switching devices and more particularly to logical pulse switching devices wherein magnetic bistable components are employed.

Magnetic bistable components are employed throughout the computer art to perform logical operations on binary information, and this invention is directed to two such operators, one of which is an Exclusive OR device, and the other of which is an Equals device. In this respect, an Exclusive OR device may be defined as having two input terminals and one output terminal at which an output signal is provided only when one or another input terminal is energized by an input signal, while an Equals device may be defined as having two input terminals and one output terminal at which an output signal is provided only when there is absence of signal input to the input terminals or when both input terminals are simultaneously energized.

Accordingly, it is then an object of this invention to provide a new and improved magnetic device adapted to perform logic on binary information which employs magnetic bistable components.

Another object of this invention is to provide a new and improved Exclusive OR device which employs magnetic bistable components.

Still another object of this invention is to provide a new and improved Equals device.

These and other objects are accomplished by constructing a device in accordance with this invention wherein first and second bistable magnetic cores are provided, each having input, output and shift winding means thereon. A first set of input windings comprising an input winding on each of the cores are serially connected to provide a first input circuit and a second set of input windings comprising further input winding on each of the cores are similarly serially connected to provide a second input circuit. The output winding means on each core are serially connected in opposite sense, and the second core is biased to one of the bistable states. The first core is adapted to be switched when any one, or both, of the input windings is energized, while the second core is adapted to be switched only when both input windings are simultaneously energized. Thus, in effect, the first core represents an OR device, while the second core represents an AND device. Since the output windings on the cores are serially connected and opposed, an output signal is provided only when either one or the other input circuit is energized. By a further provision of an inversion device, here a storage core coupled to the output winding means on the first and second cores which provides a signal in the absence of a signal output from the serially connected output windings, the inverse of the signal output provided by the first and second cores as originally described is accomplished.

Other objects of this invention will be pointed out in the following description and claims and illustrated in the accompanying drawings, which disclose, by way of example, the principle of the invention and the best mode, which has been contemplated, of applying that principle.

In the figures.

FIG. 1 is a representation of the hysteresis characteristic obtained for the magnetic material herein employed.

FIG. 2 is a circuit diagram illustrating one embodiment of this invention.

2

FIG. 3 is a circuit diagram illustrating another embodiment of this invention.

FIG. 4 is the relative timing of current pulses which are required for operation of the circuits disclosed in the FIGS. 2 and 3.

Referring to FIG. 1, the curve illustrates a plot of flux density (B) versus applied field (H) for a magnetic core having a substantially rectangular hysteresis characteristic. The opposite remanence states are conventionally employed for representing binary information conditions and are arbitrarily designated as "0" and "1." Because of these two possible remanence states of the core, it may be described as bistable. One of these states may be referred to as a "datum" state, and the other as an "information representative" state. With a zero stored, a pulse applied to a winding linking the core in proper sense causes the loop to be traversed and the remanence state "1" is attained when the pulse terminates. Such a pulse is hereinafter referred to as a "write" pulse. Similarly, the core is read out or returned to the "0" state in determining what information has been stored by applying a pulse in the reverse sense to the same or another winding. Such a pulse is hereinafter referred to as a "read" pulse. Should a "1" have been stored, a large flux change occurs, with the shift from "1" to "0" conditions with a corresponding voltage magnitude developed on the output winding. On the other hand, should an "0" have been stored, little flux change occurs in response to a read pulse and negligible signal is developed on the output winding.

30 A dot is shown adjacent to one terminal of each of the windings indicating its winding direction. A write pulse is a positive pulse which is directed into the undotted end of the winding terminal which tends to store a "1," while a read pulse is a positive pulse directed into the dotted end of the terminal and tends to apply a negative magneto-motive force, or store an "0."

The arrangements disclosed employ input and output coupling magnetic cores arranged intermediate to so called storage cores which store certain logical information. 40 These arrangements are adapted to be interconnected with each other and similar type circuitry through such coupling cores. The coupling cores may be fabricated of materials like the storage or memory cores, however, it is not essential that these cores exhibit the rectangular hysteresis characteristic required of the storage core, but should have a good B_r/B_s ratio, as these devices function as variable impedance elements in controlling the transfer of information pulses, as will be more evident in the following description. Such interconnecting coupling cores are illustrated in the circuits and labeled C_{or} , C_{and} , and C_0 for clarity.

Also shown are storage cores labeled S which are adapted to store information received. The cores S are adapted to deliver information received through the coupling core C_0 to other logical circuitry coupled therewith.

Referring now to the FIG. 2 in detail, the core S is provided with a control winding 10, which is adapted to act as both input and output winding, interconnected with an output winding 12 on the core C_{and} , and output winding 14 on the core C_{or} , and an input winding 16 on the core C_0 through a resistor R, which interconnection will hereinafter be referred to as loop A. Inputs are applied to the circuit by means of an input winding 18 on the core C_{or} serially connected with an input winding 20 on the core C_{and} , having terminals 22 and 24, and an input winding 26 upon the core C_{or} serially connected with an input winding 28 on the core C_{and} having the terminals 30 and 32, while outputs are obtained from the circuit by means of an output winding 34 on the core C_0 . The core C_{and} is energized by a clock pulse source I_A , the cores C_{or} and C_{and} are energized by a clock pulse source

I_{RA} , the cores C_{or} and S are energized by a clock pulse source I_B , while the cores C_0 and S are energized by a clock pulse source I_{RB} . A winding 36 is provided on the core C_{and} connected with the source I_A , while a winding 38 is provided on the core C_{and} and a winding 40 is provided on a core C_{or} connected with the source I_{RA} . A winding 42 is provided on the core C_{or} and a winding 44 is provided on the core S which windings are connected with the source I_B , while a winding 46 is provided on the core S and a winding 48 on the core C_0 which are connected with the source I_{RB} .

The sequence of pulses provided by the several clock pulse sources described above, is as indicated in the FIG. 4, with the time of appearance of an input signal, which is a positive signal directed into the undotted end of the input windings, shown to be the time at which the I_A clock pulse source operates, and these sources are adapted to operate with the circuits shown in the FIGS. 2 and 3.

Referring to the FIG. 2, assume all cores are in the lower remanence condition or "0" state, as is shown in FIG. 1. Initially assume no input signal to be impressed across the terminals 22-24 or 30-32. Initially, the I_A clock pulse source operates to direct a read signal into the winding 36 on the core C_{and} , which signal has no effect since the core C_{and} is already in the "0" state. Next, the I_{RA} clock pulse source operates to direct a read signal into the windings 38 and 40 on the cores C_{and} and C_{or} , respectively, which signal has no effect, since both cores are already in the "0" state. Upon termination of the I_{RA} clock pulse, the I_B clock pulse source operates to direct a signal into the windings 42 and 44 on the cores C_{or} and S , respectively, which tends to read the core C_{or} and write the core S . Since the core C_{or} is already in the "0" state it is unaffected, while the core S is switched from the "0" to the "1" state. The core S in switching to the "1" state, induces a voltage on the control winding 10 with its undotted end positive causing a clockwise current flow in loop A, which tends to read the core C_{and} and tends to write the cores C_{or} and C_0 . Since the core C_{and} is already in the "0" state, while the core C_{or} is held in the "0" state by the I_B clock pulse applied to its winding 42, the core C_0 is switched from the "0" to the "1" state. The core C_0 in switching to the "1" state induces a voltage on the output winding 34. Upon termination of the I_B clock pulse, the I_{RB} clock pulse source operates to direct a read signal into the windings 46 and 48 on the cores S and C_0 , respectively. The cores S and C_0 are switched from the "1" to the "0" state and in so doing induce a voltage on their windings 10 and 16 respectively. The induced voltages on the windings 10 and 16 are approximately equal and opposite therefore cancelling to provide very little current in loop A. Upon termination of the I_{RB} clock pulse, all cores are left in the "0" state, readying the circuit for the next cycle of operation, and an output signal has been engendered with the absence of input signals to the circuit.

Application of an input signal to the terminals 22-24 or 30-32 provides a write signal into the windings 18 and 20 on the cores C_{or} and C_{and} , or into the windings 26 and 28, respectively. Simultaneous with the application of the input signal, the I_A clock pulse source operates to direct a read signal into the winding 36 on the core C_{and} , which signal negates the write signal applied by the input to the winding 20 or 28 on the core C_{and} . The core C_{or} is switched from the "0" to the "1" state and in so doing induces a voltage on the winding 14 with the undotted end positive causing a counter-clockwise current in loop A which tends to write the core C_{and} and S while tending to read the core C_0 . Since the core C_0 is already in the "0" state and the core C_{and} is held in the "0" state by the I_A clock pulse applied to its winding 36, only the core S is switched from the "0" to the "1" state. Next, the I_{RA} clock pulse source operates to direct a read signal into the windings 38 and 40 on the cores C_{and} and C_{or} .

The core C_{or} is reset from the "1" to the "0" state and in so doing induces a voltage on the winding 14 with the dotted end positive causing a clockwise current in loop A. Resetting of the core C_{or} is performed at a sufficiently slow rate so that the voltage appearing across its output winding 14 and the value of the resistor R causes a small current flow insufficient to affect the states of the other cores coupled to the loop. Upon termination of the I_{RA} clock pulse, all cores but the core S are left in the "0" state and the I_B clock pulse source operates to direct a signal into the windings 42 and 44 on the cores C_{or} and S , respectively, which tends to read the core C_{or} and write the core S , but since the core C_{or} is already in the "0" state and the core S is already in the "1" state, there is negligible flux change. Subsequently, the I_{RB} clock pulse source operates and directs a read signal into the windings 46 and 48 on the cores S and C_0 . The core S is then reset from the "1" to the "0" state slowly, to induce a voltage on the control winding 10 with the dotted end positive causing a counter-clockwise current flow in loop A which has no effect due to the slow resetting of the S by the I_{RB} clock pulse which causes insufficient current flow in the loop A as similarly described above for resetting of the core C_{or} by the I_{RA} clock pulse. Upon termination of the I_{RB} clock pulse, all cores are left in the "0" state readying the circuit for the next cycle of operation and there has been no output signal with an input directed into the terminals 22-24. Consider an input directed across the terminals 22-24 and another input directed across the terminals 30-32. A write signal is then directed into the windings 18 and 20 on the cores C_{or} and C_{and} , respectively, while similarly, a write signal is directed into the windings 26 and 28 on the cores C_{or} and C_{and} , respectively. Simultaneously with the input signals, the I_A clock pulse source directs a read signal into the winding 36 on the core C_{and} . In this case, since both the windings 20 and 28 on the core C_{and} are energized, the bias applied by the I_A clock pulse to the winding 36 is overcome and the core C_{and} is switched from the "0" to the "1" state. The core C_{or} is also switched from the "0" to the "1" state to induce a voltage on the winding 14 with the undotted end positive while similarly the core C_{and} in switching from the "0" to the "1" state induces a voltage on the output winding 12 with its undotted end positive. The induced voltages on the windings 12 and 14, on the cores C_{and} and C_{or} , respectively, are approximately equal and their algebraic sum is effectively zero causing little current flow in loop A. Upon termination of the I_A clock pulse and the input signals, the cores C_{or} and C_{and} are left in the "1" state while the cores S and C_0 are left in the "0" state. Subsequently, the I_{RA} clock pulse source operates to direct a read signal into the windings 38 and 40 on the cores C_{and} and C_{or} , respectively, which cores reset from the "1" to the "0" state to induce a voltage on their output windings 12 and 14, respectively. The induced voltage on the windings 12 and 14, on the cores C_{and} and C_{or} , respectively, are effectively equal and opposite and therefore cancel allowing very little current flow in loop A. Upon termination of the I_{RA} clock pulse, the I_B clock pulse source operates to direct a signal into the windings 42 and 44 on the cores C_{or} and S , which signal writes the core S from the "0" to the "1" state causing a voltage to be induced on the control winding 10 with its undotted end positive causing a clockwise current flow in loop A. The current flow in loop A due to the induced voltage on the winding 10 tends to read the core C_{and} and to write the cores C_{or} and C_0 . Since the core C_{and} is already in the "0" state and the core C_{or} is held in the "0" state due to the I_B pulse applied to its winding 42, the core C_0 is switched from the "0" to the "1" state to induce a voltage on its winding 34. Upon termination of the I_B clock pulse, the I_{RB} clock pulse source operates to direct a read signal into the windings 46 and 48 on the cores S and C_0 , respectively, which resets the cores S and C_0 .

C_0 from the "1" to the "0" state. The cores S and C_0 in resetting induce a voltage on their windings 10 and 16 respectively, with their dotted end positive, which voltages are approximately equal and opposite causing little current flow in loop A. Thus, upon application of an input signal to the terminals 22-24 and 30-32 an output signal is delivered and all cores are left in the "0" state readying the circuit for the next cycle of operation. Since the circuit has delivered an output signal when none of the input signals were available or when both input signals were available, the logical operation of "Equals" has been performed.

From the circuit description and operation as described above, it may be seen that by providing a signal which switches the core S to the "1" state, in every cycle of operation, that whenever the core S is left in the "0" state, immediately prior to the application of this signal, an output is engendered. By utilizing the same type of input mode, but providing the converse of switching signal to the core S , i.e. instead of switching the core S to the "1" state switch it to the "0" state, then an output signal is provided whenever the core S is left, immediately prior to the application of the switching signal, in the "1" state. Referring to the FIGS. 2 and 3, it may be seen that the winding 42 on the core C_{or} in the FIG. 2 has been eliminated and a winding 59 on the core C_{and} , in the FIG. 3, has been added. The windings 44 and 16 on the cores S and C_0 , in the FIG. 2, are wound opposite in sense in the FIG. 3 and are primed to denote this difference, and the winding 59 on the core C_{and} is connected with the winding 44' on the core S and the clock pulse source I_B . As described subsequently, this slight variation in winding arrangement allows performance of the logical operation of Exclusive OR.

Referring again to the FIG. 3, assume an absence of inputs to the terminals 22-24 or 30-32. Initially the I_A clock pulse source operates to direct a read signal into the winding 36 on the core C_{and} , which has no effect since the core C_{and} is already in the "0" state. Upon termination of the I_A clock pulse, the I_{RA} clock pulse source operates to direct a read signal into the windings 38 and 40 on the cores C_{and} and C_{or} , respectively, which, has no effect, since both cores are already in the "0" state. Next, the I_B clock pulse source operates to direct a read signal into the windings 59 and 44' on the cores C_{and} and S , respectively, which has no effect since the cores C_{and} and S are already in the "0" state. Subsequently, the I_{RB} clock pulse source operates to direct a read signal into the windings 46 and 48 on the cores S and C_0 , respectively, which signal has no effect since both cores are already in the "0" state. Thus, with no input applied to the circuit, there is no signal output and all cores are left in the "0" state readying the circuit for the next cycle of operation.

Assume an input signal is impressed across either set of terminals 22-24 or 30-32. If the input signal is directed across the terminals 22-24, a write signal is directed into the windings 18 and 20 on the cores C_{or} and C_{and} , while, if an input signal is impressed across the terminals 30-32, a write signal is directed into the windings 26 and 28 on the cores C_{or} and C_{and} , respectively. Simultaneous with application of the input signal, the I_A clock pulse source directs a read signal into the winding 36 on the core C_{and} which negates any one of the windings 28 or 20 having a write signal impressed thereon. The core C_{or} , due to the write signal directed into its winding 18 or 26, is switched from the "0" to the "1" state to induce a voltage on the winding 14 with its undotted end positive. The induced voltage on the winding 14 due to the core C_{or} switching, causes a counter-clockwise current in loop A, which tends to write the cores C_{and} , S and C_0 . Since the core C_{and} is held in the "0" state due to the I_A clock pulse applied to its winding 36, and the winding 16' has insufficient turns for this cur-

rent to induce enough flux to shift the state of core C_0 , only the core S is switched from the "0" to the "1" state. Upon termination of the I_A clock pulse and any one of the inputs, the I_{RA} clock pulse source operates to direct a read signal into the windings 38 and 40 on the cores C_{and} and C_{or} which resets the core C_{or} from the "1" to the "0" state slowly. The core C_{or} in resetting to the "0" state induces a voltage on the winding 14 with its dotted end positive causing a clockwise current flow in loop A which has little effect due to the slow resetting of the core C_{or} . Next, the I_B clock pulse source operates to direct a read signal into the winding 44' on the core S , which resets the core S from the "1" to the "0" state to induce a voltage on the control winding 10 with the dotted end positive. The induced voltage on the winding 10 due to the core S resetting to the "1" state, causes a counter-clockwise current flow in the loop A, which tends to write the cores C_0 and C_{and} while tending to read the core C_{or} . Since the core C_{or} is already in the "0" state and the core C_{and} is held in the "0" state due to the I_B clock pulse applied to its winding 50, the core C_0 is switched from the "0" to the "1" state. The core C_0 in switching from the "0" to the "1" state, induces a voltage on the winding 34 with its undotted end positive which may be utilized by further circuitry connected thereto. Upon termination of the I_B clock pulse, the I_{RB} clock pulse source operates to direct a read signal into the windings 46 and 48 on the cores S and C_0 , respectively, which resets the core C_0 from the "1" to the "0" state. The core C_0 , in resetting from the "1" to the "0" state, induces a voltage on the winding 16' with its dotted end positive causing a counter-clockwise current in loop A which has no effect due to its slow resetting by the I_{RB} clock pulse. Upon termination of the I_{RB} clock pulse, all cores are left in the "0" state, readying the circuit for the next cycle of operation.

Assume an input signal is directed across the terminals 22-24, and an input signal is also directed across the terminals 30-32. These input signals direct a write signal into the windings 18 and 26 on the core C_{or} and a write signal into the windings 20 and 28 on the core C_{and} . Simultaneously, the I_A clock pulse source directs a read signal into the winding 36 on the core C_{and} , which signal is overcome by the simultaneous energization of the windings 28 and 20 which cause the core C_{and} to switch from the "0" to the "1" state. The core C_{or} and C_{and} in switching from the "0" to the "1" state induce a voltage on their windings 14 and 12, respectively, with their undotted end positive, which voltages are approximately equal and opposite to effectively cancel. After application of the I_A clock pulse and the input signals, the I_{RA} clock pulse source operates to direct a read signal into the windings 38 and 40 on the cores C_{and} and C_{or} , respectively, which signal resets both cores from the "1" to the "0" state to induce a voltage on their output windings 12 and 14, respectively, which voltages are equal and opposite to effectively cancel. Upon termination of the I_{RA} clock pulse, the I_B clock pulse source operates to direct a read signal into the windings 44' and 50 on the cores S and C_{and} , respectively, which signal has no effect since both cores are already in the "0" state. Similarly, subsequent operation of the I_{RB} clock pulse source which directs a read signal into the windings 46 and 48 on the cores S and C_0 , respectively, has no effect, since both these cores are already in the "0" state. All cores are left in the "0" state and upon application of both inputs to the circuit there is provided no output signal. Since an output from the circuit has been provided only when one or the other input is applied, the circuit has performed the logical operation of Exclusive OR.

In the interest of providing a complete disclosure details of one embodiment of the logical device wherein magnetic cores are employed is given below, however, it is to be understood that other component values and current magnitudes may be employed with satisfactory op-

eration attained so that the values given should not be considered limiting.

With the clock pulse currents I_A and I_B delivering a constant current of 1.8 amperes, the windings 36, 42 and 50 may comprise one turn and the winding 44 may comprise three turns. With the clock pulse sources I_{RA} and I_{RB} delivering a constant current of 1.25 amperes, the winding 46 may comprise three turns and the windings 38, 40 and 48 may comprise two turns. In the transfer loop interconnecting the coupling and storage cores, the output windings 12, 14 and 34 may comprise twelve turns, the winding 10 may comprise ten turns and the windings 16, 20, 26 and 28 may comprise five turns with the resistor R of 6 ohms.

Each of the storage and coupling cores may comprise toroids of magnesium-manganese ferrite composition having an outside diameter of 0.115 inch, inside diameter of 0.080 inch, and a thickness of 0.055 inch.

While there have been shown and described and pointed out the fundamental novel features of the invention as applied to a preferred embodiment, it will be understood that various omissions and substitutions and changes in the form and details of the device illustrated in its operation may be made by those skilled in the art without departing from the spirit of the invention. It is the intention therefore, to be limited only as indicated by the scope of the following claims.

What is claimed is:

1. A logical Exclusive OR device comprising, a storage magnetic core, a first, a second and a third coupling magnetic core, each of said cores capable of attaining bistable states of residual flux density, control winding means on said storage core, input and output winding means on each of said coupling cores, circuit means serially connecting the output winding means on said first core in opposite sense with the output winding means on said second core and connecting the control winding means on said storage core with the input winding means on said third coupling core, means connecting a first input winding on each of said first and second coupling cores, means connecting a second input winding on each of said first and second coupling cores, shift winding means on said second coupling core connected with a first clock pulse source, shift winding means on said first coupling core series connected with shift winding means on said second coupling core adapted to be energized simultaneously from a second clock pulse source, further shift winding means on said second coupling core series connected with shift winding means on said storage core adapted to be energized simultaneously from a third clock pulse source, and shift winding means on said storage core series connected with shift winding means on said third coupling core adapted to be energized from a fourth clock pulse source.

2. A logical Exclusive OR device comprising, a storage magnetic core, a first and a second input coupling core, an output coupling core, each of said cores capable of attaining bistable states of residual flux density, control winding means on said storage core, input and output winding means on each of said coupling cores, circuit means including a resistor serially connecting the output winding means on said first input coupling core opposite in sense with the output winding means on said second input coupling core and the control winding means on said storage core and the input winding means on said output coupling core, said input winding means on said first and second coupling core comprising a first input winding on each of said input coupling cores serially connected and a second input winding on each of said cores serially connected, shift winding means on said second input coupling core connected with a first clock pulse source adapted to cause said second input coupling core to be biased to a datum residual state when energized in the presence of a signal on only one of said input windings, said second input coupling core being operable

in the presence of signals on both of said input windings to shift to an information representative stable state over the opposition of the bias of said shift winding means, further shift winding means on said first input coupling core connected with shift winding means on said second input coupling core and connected with a second clock pulse source adapted to cause said first and second input coupling cores to shift to said datum residual state when energized, additional shift winding means on said second input coupling core connected with shift winding means on said storage core and a third clock pulse source adapted to cause said second input coupling core and said storage core to shift to said datum residual state when energized, and shift winding means on said storage core connected with shift winding means on said output coupling core adapted to energize simultaneously from a fourth clock pulse source and cause said storage core and said output coupling core to be shifted to said datum residual state.

3. A device as set forth in claim 2, including means for energizing said shift winding means including said first, second, third and fourth clock pulse sources, wherein said sources are actuated in sequence in the order named.

4. A logical Equals device comprising, a storage magnetic core, a first and a second input coupling core, an output coupling core, each of said cores capable of attaining bistable states in representing binary information, control winding means on said storage core, input and output winding means on each of said coupling cores, said input winding means on said first and second input coupling cores comprising a first and a second input winding wherein the first winding on each of said input cores are serially connected and the second winding on each of said input cores are serially connected, circuit means connecting the output winding means on said first input coupling core in opposite sense with the output winding means on said second input coupling core and the control winding means on said storage core with the input winding means on said output coupling core, shift winding means on said second input coupling core adapted to be energized from a first clock pulse source to bias and maintain said second input coupling core in a datum bistable state in the presence of a signal on only one of said input windings, said second input coupling core being operable in the presence of signals on both of said input windings to shift to an information representative stable state over the opposition of the bias of said shift winding means, further shift winding means on said second input coupling core connected with shift winding means on said first input coupling core adapted to be energized from a second clock pulse source and cause said first and said second input coupling core to shift to said datum bistable state, further shift winding means on said first input coupling core connected with shift winding means on said storage core adapted to be energized from a third clock pulse source and cause said first input coupling core to shift to said datum bistable state and said storage core to shift to an opposite bistable state, and shift winding means on said storage core connected with shift winding means on said output coupling core and a fourth clock pulse source to cause said storage core and said output coupling core to shift to said datum bistable state when energized.

5. A device as set forth in claim 4, including means for energizing said shift winding means including said first, second, third and fourth clock pulse sources wherein said sources are actuated in sequence in the order named.

6. A magnetic core logical circuit for receiving two input signals and for delivering an output signal indicative of the correspondence between said input signals comprising an OR core and an AND core each having an input winding for receiving each of said input signals, said AND core having a bias shift winding and a pulse source connected thereto and operable when input signals are received on said input windings to maintain said AND

core in a datum stable state in the presence of no more than one input signal, such bias having a magnitude which is overcome to shift said AND core to an information representative stable state in the presence of two input signals, said OR core being shiftable from the datum state to the information representative state in response to at least one input signal, a storage core having a control winding, said OR core and said AND core having output windings serially connected in opposition and connected in circuit with said storage core control winding and operative to shift said storage core to an information representative state only when said OR core is shifted to an information representative state while said AND core is maintained in said datum stable state, and apparatus for detecting the state of said storage core to indicate the correspondence between said input signals.

7. A logical device comprising, a storage magnetic core, first and second input magnetic cores, an output magnetic core, each of said cores being capable of attaining bistable states of residual flux density, control winding means on said storage core, input and output winding means on each of said input and output cores, circuit means serially connecting the output winding means on said first input core in opposite sense with the output winding means on said second input core and connecting the control winding means on said storage core with the input winding means on said output core, means connecting a first input winding on each of said first and second input cores, means connecting a second input winding on each of said first and second input cores, shift winding means on said second coupling core connected with a first clock pulse source, shift winding means on said first coupling core series connected with shift winding means on said second coupling core adapted to be energized simultaneously from a second clock pulse source, further shift winding means on one of said input cores series connected with shift winding means on said storage core adapted to be energized simultaneously from a third clock pulse source, and shift winding means on said storage core series connected with shift winding means on said output core adapted to be energized from a fourth clock pulse source.

8. A logical device comprising, a storage magnetic core, a first and a second input coupling core, an output coupling core, each of said cores being capable of attain-

ing bistable states of residual flux density, control winding means on said storage core, input and output winding means on each of said coupling cores, circuit means including a resistor serially connecting the output winding means on said first input coupling core opposite in sense with the output winding means on said second input coupling core and the control winding means on said storage core and connecting with the input winding means on said output coupling core, said input winding means on said first and second coupling cores comprising a first input winding on each of said input coupling cores serially connected and a second input winding on each of said cores serially connected, shift winding means on said second input coupling core connected with a first clock pulse source adapted to cause said second input coupling core to be biased to a datum residual state when energized in the presence of a signal on only one of said input windings, said second input coupling core being operable in the presence of signals on both of said input windings to shift to an information representative stable state over the opposition of the bias of said shift winding means, further shift winding means on said first input coupling core connected with shift winding means on said second input coupling core and connected with a second clock pulse source adapted to cause said first and second input coupling cores to shift to said datum residual state when energized, additional shift winding means on one of said input coupling cores connected with shift winding means on said storage core and a third clock pulse source, and shift winding means on said storage core connected with shift winding means on said output coupling core connected for energization from a fourth clock pulse source to cause said storage core and said output coupling core to be shifted to said datum residual state.
